(57) CLAIM

The ornamental design for a side posture pillow, as shown and described.

DESCRIPTION

FIG 1 is a front plan view of a side posture pillow, showing my new design, the rear plan being a mirror image thereof.

FIG. 2 is a right side elevation view of the side posture pillow of FIG. 1.

FIG. 3 is a left side elevation of the side posture pillow of FIG. 1.

FIG. 4 is a top elevation view of the side posture pillow of FIG. 1.

FIG. 5 is a bottom elevation of the side posture pillow of FIG. 1; and,

FIG. 6 is a cross sectional view as taken on line 6—6 of FIG. 1.

Portions of the side posture pillow are shown broken away in FIGS. 1, 2 and 3 to indicate indeterminate length.

The cross sectional view in FIG. 6 is shown to illustrate the exterior contour and shape of the side posture pillow of FIG. 1, not to limit the invention to the interior design or properties thereof.
